UNITED STATES PATENT OFFICE.

EDWARD JAMES, OF CLEVELAND, OHIO.

MECHANISM FOR COILING WIRE.

1,139,872.

Specification of Letters Patent. Patented May 18, 1915.

Application filed October 6, 1910. Serial No. 585,601.

To all whom it may concern:

Be it known that I, EDWARD JAMES, a citizen of the United States, and a resident of Cleveland, county of Cuyahoga, and State 5 of Ohio, have invented a new and useful Improvement in Mechanism for Coiling Wire, of which the following is a specification, the principle of the invention being herein explained and the best mode in which I have 10 contemplated applying that principle, so as to distinguish it from other inventions.

The present invention, relating as indicated to wire coiling machines, has regard more particularly to the construction of machines 15 for manufacturing flexible metal tubing of the kind that consists of two coiled wires, one within the other.

The object of the invention is the provision of a machine whereby tubing of the 20 kind just referred to may be made continuously and of any desired length.

To the accomplishment of these and related ends said invention consists of the means hereinafter fully described and particularly 25 pointed out in the claims.

The annexed drawings and the following description set forth in detail certain mechanism embodying the invention, such disclosed means constituting, however, but one 30 of various mechanical forms in which the principle of the invention may be used.

In said annexed drawings:—Figure 1 is a side elevation of one approved construction of machine embodying the invention; Fig. 35 2 is a transverse sectional view thereof taken on the line 2—2, Fig. 1; Fig. 3 is similarly a transverse sectional view taken on the line 3—3, Fig. 1; Fig. 4 is an enlarged sectional view of the mandrel and two of the 40 rolls that coöperate therewith, the plane of the section being indicated by the line 4—4 Fig. 1; Fig. 5 is a broken detail view, on a like enlarged scale, of two of said rolls; Figs. 6 and 7 are views, corresponding with 45 Fig. 4, and respectively showing two modifications in the construction of the rolls; and Fig. 8 illustrates yet another modification in this particular.

The present invention provides a machine 50 which constitutes an improvement on the machine disclosed in my co-pending application for United States Patent, Serial No. 558,346, filed April 29, 1910.

By the improved method involved in the 55 operation of the present machine, I propose to simultaneously coil both wires, the one

within the other, whereby as will be obvious, a completed tube of the character in hand is at once formed. Furthermore, instead of winding such wires in place on a 60 mandrel extending the length of the coil, thereby limiting the length of the coil and thus of the tube, I wind the wires on a mandrel or equivalent forming member, that does not necessarily have a longitudinal 65 movement, so that no such limitation is imposed on the length of the tube that is formed.

The coiling mechanism proper of my improved machine comprises in the form illustrated, a short mandrel 1, (Figs. 1 and 4) that is preferably rotatably mounted in a suitable supporting head 2. It is not intended to positively drive such mandrel, however, but simply to leave it free to rotate 70 under the action of the coil being formed thereon. Said mandrel, in the form shown in the figures just referred to, comprises two co-axial, substantially cylindrical sections of unlike diameters, the section nearest to the head 2, or in other words, adjacent to the supported end of the mandrel, being of larger diameter than the free end. Said mandrel is furthermore desirably made hollow, so as to be adapted to permit of the 75 introduction therein of a suitable lubricant, which is preferably maintained under pressure sufficient to cause it to be gradually discharged through openings 17, 17 in the mandrel's cylindrical walls. Such lubricant 80 may be thus supplied through a chamber 18 in the head 2, that provides a convenient reservoir.

For many uses it has been found desirable to interiorly lubricate the type of flexible metal tubing, consisting of inter-coiled wires such as the present machine is adapted to manufacture, not only that the bore of such tube may be thus coated, but also the bearing, or contacting, portions of the successive convolutions of the inter-coiled wires. By the foregoing construction, enabling as it does the introduction of the lubricant and its thorough spread within the convolutions of the coils formed on the respective sections of the mandrel, both of these desirable results are accomplished simultaneously with the winding of the coils.

Symmetrically disposed about such mandrel, and parallel therewith, are three shafts 110 3, 4 and 5, each of the two lower of which (viz. shafts 3 and 4) is preferably jour-

naled in spaced, fixed bearings 6, 6, while the uppermost is supported in a frame 8 oscillatory about an axis 9 parallel with the shaft, but capable of supporting said shaft 5 at an adjustable distance above the mandrel 1, this distance being gaged by a hand wheel 10 threaded upon a vertically disposed screw 11, and bearing upon the free end of said frame through an interposed compression 10 spring 12.

In addition to bearings 6, 6 for the shafts 3 and 4, I provide thrust bearings 7 (Fig. 3), to take up any end thrust to which such shafts may be subjected incidentally to the 15 operation of the wire-coiling rolls respectively carried thereby. The function of these rolls is to guide the respective wires W and w, that enter into the making of the tubing, about the mandrel 1 as well as to 20 maintain them in contact therewith. Of such rolls the two lowermost are of substantially similar construction, (viz. that shown in Fig. 3) being composed of two sections, 13 and 14, the first being keyed or 25 otherwise fixedly secured to its shaft, and the other being freely rotatable about such shaft, preferably upon a hub-like extension 15 of the first section. Both these sections are peripherally grooved, so as to provide 30 on their outer, cylindrical faces a series of encircling corrugations 16; one form of which is shown in Figs. 4 and 5. These particular encircling corrugations are designed to engage with the turns of the wire 35 W being coiled on the mandrel section of larger diameter. Accordingly on the portions of the respective rolls that coöperate with the mandrel section of larger diameter such corrugations are more closely spaced 40 axially of said rolls, than on the other portions of such rolls which extend beyond the offset or step between the mandrel sections of larger and smaller diameter. In other 45 words, the corrugations on the first roll sections 13, correspond with the closely crowded turns or convolutions of the first coil W as it is wound on the first mandrel section, whereas the convolutions on the second roll section correspond with the spaced condition 50 of such convolutions after the second coil has been introduced within the first. The second, or outer, roll-section 14, then, is provided with elements or ribs 19 lying intermediate between the corrugations 16 just described, which elements are of such a radius as to project a sufficient distance beyond said corrugations to contact with the convolutions of the inner coil w, that is introduced at this stage of the operation. 55 Preferably, moreover, such elements or ribs of the roll are likewise grooved, so as to present corrugations, the more effectively to contact with and form these last-named convolutions. This, however, is not essential 60 and such ribs on the second roll section may 65

be left straight if desired, as shown for example in Fig. 8.

Between the two lowermost coiling rolls thus described as substantially identical, there exists this difference, viz. that the foremost roll, regarding the same in the direction in which the wire is fed, is cut away on its inner side, or otherwise spaced from the abutting portion of the machine frame, as by the introduction of a washer or disk of suitable thickness, so as to leave a space 20, (see Figs. 5 and 8) through which the wire W that forms the outer coil, may pass directly on a line from its corresponding feed rolls to the mandrel; that is to say, on a line tangent to such mandrel, as clearly shown in Fig. 1. It will be observed, in other words, that if such wire were fed in over the coiling roll to the mandrel, an extra bend, or kink, would be introduced in the wire, and that, too, in a direction opposite to the one which it is to receive upon being coiled on the mandrel. This result will follow no matter from what direction the wire be brought in between the rolls. By the arrangement just described however, I avoid this entirely and thus save the wire the additional strain that would be imposed upon it by being twice bent upon radii so short and close together. Similarly a space 21 is left between the two sections 13 and 14 of this foremost roll, through which the second wire w may pass directly on a line tangent to the mandrel, thus avoiding kinking it likewise.

The upper roll of the three coiling rolls is illustrated as being simply an idler; but just as in the case of the two previously described rolls, it is formed of two sections 22 and 23 (see Fig. 4). Since this roll is utilized in the present machine merely to press down upon the coils of wire being formed about the mandrel by the two positively driven coiling rolls, I have found it advisable to dispense with corrugations on at least the first section 22 of such roll, inasmuch as a roll with a smooth surface will be just as effective to hold the convolutions of the initially formed portion of the outer coil against the mandrel as would a corrugated roll. The second section 23 may likewise be left plain if desired, although, here, in order to assist in spreading apart the convolutions of the outer coil, thus initially formed closely together, I prefer to employ 110 the corrugations 16 with the projecting intermediate ribs 19 adapted to coöperate with the inner coil that is now introduced.

The outwardly directed edges 24 of all three rolls, moreover, that is the edges directed away from the head 2, and in the direction of discharge of the finished tubing, are beveled as indicated in Fig. 4, since I have found that thereby the quick recoil of the wires, and particularly of the outer 130

wire W, which otherwise follows the release of the tube for the coiling rolls, may be restrained and the tubing allowed to assume its normal condition as to internal tension, 5 easily and gradually.

It will be understood, of course, that either the rolls or the encircling corrugations thereon are set relatively to each other, so that the first corrugation that receives the 10 wire will be a little in advance axially (or in the rear as one may be pleased to regard it,) of the second corrugation, and so on, in order that a proper spiral may be formed, (see Fig. 5). Where three symmetrically 15 disposed rolls are utilized, as in the present construction, there will be a displacement in the corrugation of successive rolls equal to one-third of the pitch of such spiral, as will be readily apparent. I prefer to secure the 20 offsetting in question by correspondingly offsetting the entire roll, since this is readily accomplished by simply interposing a washer 25 of the proper thickness between the rear edge of the roll and the head or 25 frame in which its shaft is journaled.

Of the three shafts hereinbefore described as bearing the wire-coiling rolls, the two lowermost along with certain feed-rolls 28 and 29 presently to be described, are driven 30 in unison from a common drive-shaft 26 (Figs. 1, 2 and 3) preferably by means of worm gearing 27, although this obviously is a matter of indifference. The intermediate roll, viz. the one carried in the adjustable frame 8 above the mandrel, is preferably not positively driven, as this has been found unnecessary under ordinary operating conditions. It will be readily understood how it can be connected to be positively driven, if desired, from the same 40 shaft as the other two rolls, or from a counter-shaft connected therewith.

There are two pairs of the feed rolls 28 and 29 just referred to, as shown in Fig. 2, 45 such pairs of rolls being laterally spaced from each other so as to feed the wires W and w passing therebetween respectively, at the proper points longitudinally of the mandrel 1; in other words, the second wire is 50 spaced from the first a distance substantially equal to the length of the mandrel section of larger diameter that projects beyond the mandrel supporting head 2, it being upon this section that the outer wire constituting 55 the tube is initially wound before its convolutions are separated by the introduction of the second coil. Of these two pairs of feed-rolls the lowermost rolls of each are mounted upon shafts 30 and 31, journaled in the 60 frame of the machine and driven, as above indicated, from the main drive-shaft 26 that also drives the two lowermost of the wire-coiling rolls. The upper feed rolls are also positively driven, their shafts 32 and 33 being 65 intergeared with the corresponding

lower shafts. Such upper shafts, however, are journaled in a common movable frame 34, preferably one oscillatory about an axis 35 transverse to the shafts and adapted to be pressed down under a variable pressure by means of a hand-wheel 36 mounted upon a threaded shaft 37 and operating through an interposed spring 38 similar to that employed in connection with the uppermost coiling roll. 75

Intermediately between the respective pairs of feed rolls, that thus feed in the two wires used in forming the tube, and the coiling rolls, which wind such wires into tubular form, I provide tubes 39 of suitable 80 length, through which the wires may pass. These tubes are designed to contain a suitable lubricant, preferably, one containing graphite as a constituent, which lubricant may be supplied as required through a feed 85 opening 40 so that the wires as they are fed forwardly onto the mandrel, or rather into the coiling rolls, are thoroughly coated with the lubricant in question.

It will be understood, of course, that 90 changes may be made both in the detailed construction of the rolls and the manner of feeding the wire thereto to suit the necessity or convenience of particular operations. For example, it is conceived that one large 95 field of use for flexible metallic tubing of the kind in hand, will be to incase insulated conductors or to form, in other words, what is known as electrical conduits, underwriters and others demanding nowadays, 100 that such conductors be thoroughly protected against injury to their insulation as this is a frequent cause of fire in modern buildings. While the tubing may be 105 formed independently of the insulated conductor and the latter then slipped therethrough, I have found it entirely practical to wind such tubing directly upon the cable, thereby much facilitating and cheapening 110 the cost of manufacture of the product.

The proposition is obviously substantially 115 the same where, instead of the insulated electrical cable, it is desired to armor rubber hose, or any similar object. My improved flexible metal tubing may be directly formed on such hose in exactly the same fashion as that in which I have just described it as being wound upon the insulated conductor. The term conductor, accordingly will hereinafter be employed to 120 connote either of these two products, or any similar product to which my tubing may be thus applied. I have furthermore found that where the coils are being wound on an insulated electrical conductor in the production of an armored conduit, such as just described, it is advantageous to so gage the 125 diameters of the interlocking wire coils, that the convolutions of the inner one shall be more or less effectively embedded in the 130

insulation of the conductor, since I am thus enabled to use a lighter gage of wire, while still providing an equally effective covering or armor for the conductor. In other 5 words, the embedded coil will receive and take up a greater longitudinal strain for a given gage of wire than if it were the inner coil of a simple tube or of such a tube only loosely incasing the conductor.

10 A modification in the machine, adapting it for such operation is illustrated in Fig. 6, where it will be observed that the modified mandrel 41 comprises a single section of uniform diameter corresponding with the 15 section of larger diameter in the case of the mandrel previously described. Such mandrel is furthermore open at both ends and the insulated conductor C, which is to be incased, is passed directly therethrough, 20 the diameter of the mandrel bore being properly gaged to fit closely about the conductor. The latter thus replaces, in effect, the mandrel section of smaller diameter and the operation of inter-coiling the two 25 wires that go to make up my improved tubing; may proceed just as before, the outer wire being coiled upon the mandrel section of larger diameter that is retained, while the smaller wire is coiled upon the conductor. 30 The latter, it will be understood, is allowed to move longitudinally through the mandrel as the inner wire is thus coiled thereon, thus differing from the mandrel section of smaller diameter in the preceding 35 construction.

It is desirable as before, that the tube should be interiorly lubricated and to this end the reservoir 18 in the head 2 is constructed so as to permit the conductor to be 40 drawn directly therethrough, it being found that sufficient lubricant will adhere thereto to effect the desired purpose.

A further modification is shown in the figure just referred to in that the inner, 45 or smaller, wire w' as it has been previously termed, is of half-round section, instead of being a circular wire of smaller diameter than outer wire W.

It will be understood, of course, that my 50 improved machine is not limited to use with any particular cross-section of wire strand; but such strand may be either circular, or half-round, or angular, as may be found suitable to the production of tubing 55 of the general class in hand. Thus in Fig. 7, I illustrate the use, for one of the wires, of a strand w' of triangular cross-section; such strand, moreover, is here shown as being the outer one despite the fact that it 60 is introduced at a point in the operation corresponding with the introduction of what has in the preceding cases figured as the interior coil. Accordingly the second section of the respective rolls is here left 65 plain, that is, without corrugations and this

second wire w' simply pressed into place, correspondingly spreading the turns of the interior coil. In this operation no mandrel section of smaller diameter is, obviously, necessary and so it is accordingly omitted 70 in the showing of Fig. 7.

It has been previously explained that the projecting elements or ribs between the corrugations 16, in the case of the second or outermost sections 14 and 23 of the rolls, 75 may be left smooth, that is so as to present a cylindrical surface instead of being concave so as to present corrugations. The smooth superficial form of these ribs is illustrated in Fig. 8. On the other hand, were a strand w' 80 of triangular section to be introduced as the inner coil in the way strand w' is introduced in Fig. 6, these ribs might be made with an angular depression to fit the contour of the wire. 85

In each of the several forms of my improved machine illustrated in the drawings hereinbefore described there will be, owing to the use of the feed rolls, but little tension, if any, on the wires between such feed rolls 90 and the coiling rolls. It will be understood, however, that in place of thus pushing the wires, as it were, upon the mandrel and simply employing the coiling rolls to bend the same onto such member, I might rely on the frictional engagement of the rolls with the turns of wire about the mandrel to pull the latter, thus making the coiling mechanism, proper, self-feeding. Under certain operative conditions, moreover, the positive driving of the coiling rolls might be omitted entirely and full reliance placed on the feed rolls to force the wire or wires onto and about the mandrel. 95

Where the feeding of the component 105 wires, the interposed convolutions of whose coils go to make up my improved tube, is accomplished by pushing such wires into the coiling members, whether rolls or dies, the use of the mandrel may be dispensed with. 110 This is in effect exemplified in the construction shown in Fig. 6, where the second wire may be either pushed in, to directly surround the insulated table so as to only lightly engage therewith, or where it may 115 be drawn in about the same by the pulling action of the rolls; in the first case the presence of the cable will be only incidental, while in the second it will obviously function as a mandrel. 120

Other modes of applying the principle of my invention may be employed instead of the one explained, change being made as regards the mechanism herein disclosed, provided the means stated by any of the following claims or the equivalent of such stated means be employed. 125

I therefore particularly point out and distinctly claim as my invention:—

1. In a machine of the class described, a 130

- wire-coiling roll comprising a plurality of axially alined, independently rotatable sections, each formed with encircling corrugations and adapted to coöperate with the 5 turns of a wire being coiled, the corrugations on one section being differently spaced axially of the roll than those on the other section, but the corrugations on the respective sections being substantially uniformly spaced. 10
2. In a machine of the class described, the combination of a plurality of rolls mounted with their peripheral faces adjacent to each other and adapted to coil a wire therebetween, said rolls respectively comprising two axially alined, independently rotatable sections, each formed with encircling corrugations and adapted to coöperate with the turns of a wire being coiled, the corrugations 15 on one section being more closely spaced axially of the roll than those on the other section, but the corrugations on the respective sections being substantially uniformly spaced. 20
3. In a machine of the class described, the combination of three substantially cylindrical rolls having parallel axes and mounted with their cylindrical faces adjacent to each other and adapted to coil a wire therebetween, the axes of two of said rolls being fixed and the third being movable toward and away from such two, two of said rolls respectively comprising two axially alined, independently rotatable sections, each 25 formed with encircling corrugations and adapted to coöperate with the turns of a wire being coiled; the corrugations on one section being more closely spaced axially of the roll than those on the other section, but the corrugations on the respective sections being substantially uniformly spaced. 30
4. In a machine of the class described, a wire-coiling roll comprising two sections, each formed with encircling corrugations 45 adapted to coöperate with the turns of the wire being coiled, the corrugations on one section being more closely spaced axially of the roll than those on the other section, the section bearing the more closely spaced 50 corrugations being positively driven and the other rotatable independently thereof.
5. In a machine of the class described, a wire-coiling roll comprising two independently rotatable sections, each formed with 55 corrugations adapted to coöperate with the turns of a wire being coiled, the corrugations on one section being more closely spaced axially of the roll than those on the other section; and other corrugations, between the 60 more widely spaced corrugations on said last-named section, adapted to coöperate with the turns of a second wire.
6. In a machine of the class described, a wire-coiling roll comprising two independently 65 rotatable sections, each formed with
- corrugations adapted to coöperate with the turns of a wire being coiled, the corrugations on one section being more closely spaced axially of said roll than those on the other section; and other corrugations, between the 70 more widely spaced corrugations on said last-named section, such other corrugations projecting beyond the first named, so as to be adapted to coöperate with the turns of a second wire coiled within said first wire. 75
7. In a machine of the class described, the combination of a wire-coiling roll comprising two sections each formed with encircling corrugations adapted to coöperate with the turns of a wire being coiled, the 80 corrugations on one section being more closely spaced axially of said roll than those on the other section; other corrugations, between the more widely spaced corrugations on said last-named section, adapted to 85 coöperate with the turns of a second wire; and means for positively rotating said first-named section, said last-named section being rotatable independently thereof.
8. In a machine of the class described, the combination of a wire-coiling roll comprising two sections each formed with encircling corrugations adapted to coöperate with the turns of a wire being coiled, the corrugations on one section being more 90 closely spaced axially of said roll than those on the other section; other corrugations between the more widely spaced corrugations on said last-named section, such other corrugations projecting beyond the first named, 95 so as to be adapted to coöperate with the turns of a second wire coiled within said first wire; and means for positively rotating said first-named section, said last-named section being rotatable independently 100 thereof.
9. In a machine of the class described, the combination of a mandrel, one section of the mandrel being of larger diameter than another; and a substantially cylindrical wire-coiling roll having its cylindrical face disposed alongside said mandrel, said roll comprising a plurality of axially alined, independently rotatable sections, respectively adapted to coöperate with turns of 110 wire being coiled on the adjacent mandrel sections. 115
10. In a machine of the class described, the combination of a mandrel, one section of the mandrel being of larger diameter than another; and a substantially cylindrical wire-coiling roll having its cylindrical face disposed alongside said mandrel, said roll comprising two axially alined, independently rotatable sections, each formed 120 with encircling corrugations and respectively adapted to coöperate with turns of wire being coiled on the mandrel sections of larger and smaller diameter. 125
11. In a machine of the class described, 130

- the combination of a mandrel supported at one end and having its other end free, the section of the mandrel adjacent to its supported end being of larger diameter than the remainder; and a substantially cylindrical wire-coiling roll having its cylindrical face disposed alongside the mandrel, said roll comprising two axially alined, independently rotatable sections respectively 5
5 coöperative with the mandrel sections of larger and smaller diameter, the roll sections being each formed with encircling corrugations adapted to coöperate with the turns of a wire coiled on the mandrel section of larger diameter, the corrugations on the roll section adjacent to the mandrel section of larger diameter being more closely spaced axially of the roll than those on the roll section adjacent to the mandrel section of smaller diameter. 10
10 12. In a machine of the class described, the combination of a mandrel supported at one end and having its other end free, the section of said mandrel adjacent to its supported end being of larger diameter than the remainder; and a wire-coiling roll having its cylindrical face disposed alongside said mandrel, said roll comprising two independently rotatable sections, each formed with encircling corrugations adapted to engage with the turns of a wire coiled on the mandrel of larger diameter, such corrugations on the section of said roll adjacent to such mandrel-section being more closely spaced than on the roll-section adjacent to the mandrel-section of smaller diameter, and other corrugations between the more widely spaced corrugations on said last-named roll-section adapted to engage with the turns of a wire being coiled on said mandrel-section of smaller diameter. 15
15 13. In a machine of the class described, the combination of a freely rotatable mandrel, one section of said mandrel being of larger diameter than another, and a wire- 20
